UNITED STATES PATENT OFFICE.

JOSEPH P. ARNTZ, OF CANAL FULTON, OHIO.

WINDOW-BRACKET.

1,373,397.

Specification of Letters Patent. Patented Apr. 5, 1921.

Application filed March 22, 1920. Serial No. 367,763.

To all whom it may concern:

Be it known that I, JOSEPH P. ARNTZ, a citizen of the United States, residing at Canal Fulton, in the county of Stark and State of Ohio, have invented a new and useful Window-Bracket, of which the following is a specification.

This invention relates to brackets for use in supporting curtain rods and shades and is an improvement over my prior Patent No. 1,283,029 dated October 29, 1918; and the objects of the invention are to provide a bracket of simple, ornamental, and rigid construction which may be readily applied to and secured in the desired position upon a window frame or the like, means being provided for adjusting the bracket in order that it may be secured to the side or to the top of the window frame.

Other objects are the provision of a universal connection between the curtain rods and the bracket which is reversible in order to connect either the inner or outer curtain rod to the bracket.

Further objects are the provision of an adjustment whereby the bracket may be adjusted to fit window frames of varying thickness.

With these objects in view the invention consists in the novel construction and arrangement of parts, hereinafter described, illustrated in the accompanying drawings, and particularly pointed out in the appended claims, it being understood that various changes in the form, proportions, size and minor details of construction may be made within the scope of the appended claims, without departing from the spirit or sacrificing any of the advantages of the invention.

The invention thus set forth in general terms is illustrated in the accompanying drawings forming part hereof, in which—

Figure 1 is a plan view of a bracket showing portions of the curtain rod and shade carried thereby.

Fig. 2 is a front elevation of the same.

Fig. 3 is a section on the line 3—3, Fig. 2.

Fig. 4 is an elevation of the bracket adjusted for securing to the top of the window frame.

Fig. 5 is an elevation of the bracket with the attaching means removed arranged to be

connected to the window frame by nails or the like.

Fig. 6 is a detail perspective view of the several parts of the bracket detached.

Fig. 7 is a detail perspective view of one of the angular connecting members by means of which the curtain rods are connected to the bracket.

A practical embodiment of the invention is disclosed in the accompanying drawings forming a part of this specification in which similar numerals of reference indicate corresponding parts throughout the several views.

The bracket proper comprises four principal parts: the channel shaped securing portion, comprising the members 1 and 2 which are adjustably connected together, the supporting plate 3 which is provided with prongs for attaching the curtain rods and the sliding plate 4 which is provided with the shade fixture 5.

The member 1 comprises the plate 6 having the angular jaws 7 provided with means for positively preventing the bracket from slipping downward out of position, such means preferably consisting of an inturned lip 8 formed upon one of the horizontal edges of each jaw 7, said lips being sharpened so that when the jaws of the bracket are driven into position over the edges of the window frame, said lips will cut into the rear surface of the finishing board of the window frame and positively engage the same to prevent downward movement thereon.

The portion 6 of the member 1 and the angular portion 9 of the member 2 are provided with the corresponding ribs and grooves 10 and 11 respectively arranged to be nested as best shown in Fig. 3 of the drawings, apertures 12 being formed in the ribs 10 and elongated slots 13 being formed in the ribs 11, bolts 14 being located through said slots and apertures for the purpose of holding the members 1 and 2 in any desired adjustment.

The plate 15 of the member 2 is provided near its upper and lower edges with the horizontal slots 16, the metal between said slots and the horizontal edges of the plate being curved inwardly as shown at 17 in order that the channel shaped securing por-

tion of the bracket may be more readily sprung into position over the edge of the board.

The member 2 is provided with an outwardly pressed square projection 18 adapted to be seated within the similar indentation 19 formed in the supporting plate 3. The supporting plate is provided with the outwardly disposed integral, angular flanges 20 upon the upper portions of which are formed the down turned, rearwardly disposed prongs 21 which are spaced from the upper edges of the flanges 20; these prongs being arranged to receive the angular connecting members carried by the curtain rods. Apertures 22 are provided in the supporting plate for the purpose of connecting the same directly to the window casing by nails or the like, as will be later described.

The slidable plate 4 is provided with the outwardly pressed channel portion 23 arranged to be slidably mounted upon the projection 19 and is provided with an elongated horizontal slot 24 arranged to register with the apertures 25 and 26 in the projections 18 and 19 respectively, a bolt 27 being located through said apertures and the slot and provided with the wing nut 28 by means of which the parts 2, 3 and 4 are clamped together in any desired adjustment.

The bracket thus provided is especially adapted for supporting the cross sectional channel shaped extensible curtain rods 29 which are at present in common use. The angular attaching members 30 are provided for connecting the curtain rods to the supporting plate 3, each of these angular members preferably comprising a comparatively long arm 31 and a comparatively short arm 32, each of said arms being provided near its outer extremity with a square aperture 33 having a reduced slot 34 communicating therewith. A half round rib 35 is formed in the member 30 in order to cause the same to fit snugly within the channel shaped curtain rods. The longer arm 31 is located within the end of the inner curtain rod and the shorter arm 32 within the end of the outer curtain rod thus properly spacing the rods from the bracket. In placing the curtain rods in position upon the supporting plate the aperture 33 is placed over the prong 21, the prong passing through the slot 34, the connecting member being then moved downwardly until the upper edge of the aperture 33 rests upon the restricted portion 36 of the prong.

The members 1 and 2 are adjusted to accommodate the thickness of the finishing board A of the window frame and the nuts upon the bolts 14 are tightened. If it is desired to engage the side of the window frame the supporting plate 3 is mounted in a position shown in Fig. 2, the wing nut 28 being tightened to hold the several parts in

the adjusted position. If, however, it is desired to engage the top of the window frame, the wing nut 28 is loosened sufficiently to allow the supporting plate to be given a quarter turn with reference to the member 2 the wing nut being then tightened, bringing the parts into the relative position shown in Fig. 4.

The channel shaped securing portion of the bracket is then driven into position over the edge of the board, the lips 8 cutting into the board and positively engaging the same to prevent downward movement thereon while the clamping action of the curved jaws 17 will hold the bracket in position on the board.

If it is desired to use the bracket without the channel shaped securing portion the members 1 and 2 may be removed and the bolt 27 passed only through the aperture 26 and the slot 24 clamping the supporting plate and the slidable plate, together in any desired adjustment. The supporting plate may then be attached to the window frame by driving nails or the like through the apertures 22 therein.

It will thus be evident that I have provided a bracket which may be readily and easily adjustable to be applied to a window frame or the like of penetrable material and which may be firmly clamped in position and positively held against downward movement thereon without defacing exposed surfaces, the adjustments provided allowing for either side or top engagement of the bracket upon the window frame.

I claim:

1. A bracket for the finishing board of a window frame or the like comprising a channel shaped securing portion with jaws adapted to embrace opposite sides of the edge portion of the finishing board, a squared projection formed upon the securing portion, a curtain rod supporting plate provided with a squared socket to receive said squared projection, a shade fixture provided with a channel portion slidably mounted upon the squared socket of said supporting plate and provided with an elongated slot and a bolt located through said squared projection and socket and through said slot for holding said parts in the desired adjustment.

2. A bracket for the finishing board of a window frame or the like comprising an attaching plate having an inturned angular portion at one vertical edge, an angular member adjustably connected thereto, said attaching plate and angular member being arranged to embrace opposite sides of the same edge portion of the finishing board, a square projection formed upon the attaching plate, a curtain rod supporting plate having a square projection formed therein, and adapted to receive the square projection upon the attaching plate, said curtain rod

supporting plate being provided with attaching prongs to connect a curtain rod thereto, a shade fixture provided with a channel portion slidably mounted upon the square pro-

5 jection of the curtain supporting plate and provided with an elongated slot, and a bolt located through the square projections of the attaching plate and curtain rod supporting

plate for holding the curtain rod supporting plate in fixed relation to the attaching plate 10 and allowing longitudinal adjustment of the shade fixture.

In testimony that I claim the above, I have hereunto subscribed my name.

JOSEPH P. ARNTZ.
